UNITED STATES PATENT OFFICE.

GRAVES R. MAUPIN, OF MOBERLY, MISSOURI, ASSIGNOR TO THE J. FAESSLER MANUFACTURING COMPANY, OF MOBERLY, MISSOURI, A COPARTNERSHIP.

METHOD OF AND APPARATUS FOR REMOVING SCALE AND EXPANDING BOILER FLUES.

Application filed January 19, 1922. Serial No. 530,456.

To all whom it may concern:

Be it known that I, GRAVES R. MAUPIN, a citizen of the United States, and resident of the city of Moberly, county of Randolph, 5 and State of Missouri, have invented certain new and useful Improvements in Methods of and Apparatus for Removing Scale and Expanding Boiler Flues, of which the following is a specification containing a full, clear, 10 and exact description, reference being had to the accompanying drawings, forming a part hereof.

My invention relates to improvements in the method of and apparatus for removing 15 scale and expanding boiler flues, and has for its primary object the method of and apparatus for removing the scale which accumulates around a boiler flue at its junction with the flue sheet.

20 A further object is to construct an apparatus for removing the scale at the junction of a boiler flue and a flue sheet, which apparatus if so constructed as to exert only radial pressure on the flue—all lateral pressure being imparted to the flue sheet.

In the drawings,

Fig. 1 is a longitudinal section of my apparatus, showing the same in position within a boiler flue.

30 Fig. 2 a side elevation of my improved apparatus with the mandrel removed.

Fig. 3 an end elevation of the same, looking in the direction of the arrow 3.

35 Fig. 4 an end elevation of the same, looking in the direction of the arrow 4.

Fig. 5 a side elevation of the expander mandrel.

Fig. 6 an end view of the same.

40 Fig. 7 an enlarged side elevation of one of the expander segments.

Fig. 8 an end view of the same.

In the construction of my device, 9 represents a flue sheet, and 10 a flue. The flue sheet is provided with openings 11, in which 45 are seated copper gaskets 12. These gaskets being flush with the outer face of the flue sheet and extending into the boiler. The ends of the flue 10 are reduced in size, as indicated at 13. This reduced portion 50 is inserted in the gasket 12, so that a portion of the flue extends through the sheet 9. The tube 10 is then expanded within the gasket, so as to form a tight fit between it and the gasket 12, and between the gasket 55 12 and the openings 11 formed in the flue

sheet, while the portion of the flue immediately to the rear of the flue sheet 9 is beaded, as indicated by the numeral 14, as is that portion of the gasket 12 to the inside of the flue sheet. The projecting end of the tube 60 10 is beaded over as at 15, thus tightly securing the flue within the sheet. After this joint has been thus formed, the practice at the present time is to weld this bead to the sheet 9, as indicated by the numeral 16. 65 This is done by what is known as arc welding. After the boiler has been used a short time, scale will commence to accumulate between the gasket 12 and sheet 9, as indicated by the letter "S." This scale gradually extending on to the flue and assumes the shape of a fillet. It is this scale which my method and apparatus is designed to remove, since the use of boiler compounds does not prevent the formation of scale at this point, 70 and if the scale is not removed, the flues will burn out at the point. My apparatus consists of an expander which is circular in form, and formed of a plurality of segments 17. These segments are provided 75 on one end with an enlarged cylindrical portion 18, which is provided with a groove 19, and in to this groove 19 is sprung a flat circular spring 20. This is for the purpose of holding the segments in assembled 80 form. Adjacent the cylindrical portion 18 is a reduced cylindrical portion 21 which is designed to contact with the flue and expand it in the flue sheet. The cylindrical portion 21 has an enlarged rounded portion 22 which 85 is adapted to enter the bead 14.

It will be noted from Figs. 3 and 4 that when the segments are assembled, a polygonal opening is formed therethrough. This opening being smaller at the end 23 than at 90 the end 24.

It will also be noted from Fig. 7, that the rear portion which forms the opening in each segment has a greater inclination than the forward portion, so that when the mandrel 25 is driven in, it will contact only with the forward portion and exert all its pressure there, as there is no pressure needed at the back end of the expanded. The enlarged cylindrical portion 18 is seated 100 within a cage 26. This cage is provided with three extending feet 27 which rest against the flue sheet just outside of the weld. This cage is provided with a central opening 28, in which the cylindrical por- 105 110

tion 18 is located, and the expander is held within the cage by means of the washer 29 which rests against the shoulder 30 formed in the cage, and this washer is in turn held 5 by means of a spring 31 which is seated in a groove 32.

It will be noted that the opening 33 through which the cylindrical portion 21 passes is of larger diameter than the cylindrical portion 21. This is for the purpose 10 of allowing the cage to be so placed that it will clear all of the welded portion and still allow the expander to be placed in the flue. In other words, it takes care of any variation 15 of width of metal deposited through the welding. The mandrel 25 is provided with a tapered portion 34. This tapered portion having a number of flat faces equal in number to the number of segments in the 20 expander.

The operation of my device is as follows:

After the boiler has been in use for a time, the scale "S" commences to form. When the boiler is to be cleaned, the expander 25 is inserted as in Fig. 1, and the mandrel 25 inserted through the opening and driven in. This driving in of the mandrel expands the tube or flue, thus cracking the scale, while a certain amount of vibration is 30 imparted to the flue sheet 9 by means of the blows given the mandrel which will jar the scale, previously cracked, loose and dislodge it from the flue sheet and around the flue. It will be seen from this operation, that not 35 only is the scale removed, but the flue further tightened in the flue sheet, and during this operation no lateral pressure is exerted on the flue. Any lateral pressure is trans-

mitted to the flue sheet through the cage 26 and feet 27, so that there is no possibility 40 or danger of loosening the flue in the sheet by putting pressure directly against the beaded end 15 of the flue.

Having fully described my invention, 45 what I claim is:

1. The method of removing scale around the tube and inside of the flue sheet of a boiler, which consists in expanding the tube adjacent the flue sheet so as to crack the deposited scale, and simultaneously therewith 50 imparting vibration to the flue sheet thereby jarring loose the accumulated scale.

2. The method of removing scale from boiler tubes adjacent the flue sheet, which consists in cracking said scale, and simultaneously with said cracking imparting vibration to the flue sheet thus jarring said 55 cracked scale from its position.

3. An apparatus for removing scale from boiler flues adjacent the flue sheet, comprising a flue expander composed of segments, a flat spring ring for holding said segments in assembled form, a tapered mandrel for spreading said segments apart, a cage adapted to contact with the flue sheet at points 60 around the flue, said cage adapted to have the expander removably located therein, and removable means carried by said cage for securing the expander therein, said expander and cage adapted to simultaneously exert 65 an expanding strain on the flue and impart vibration to the flue sheet.

In testimony whereof I have signed my name to this specification.

GRAVES R. MAUPIN.
